UNITED STATES PATENT OFFICE.

EUGENE CHILDS, OF BOSTON, MASSACHUSETTS, ASSIGNOR TO THE TRIMONT MANUFACTURING COMPANY, OF SAME PLACE AND PORTLAND, MAINE.

DESIGN FOR A ROTARY-TRIMMER-CUTTER BODY.

SPECIFICATION forming part of Design No. 30,678, dated May 2, 1899.

Application filed March 29, 1899. Serial No. 711,018. Term of patent 14 years.

To all whom it may concern:

Be it known that I, EUGENE CHILDS, a citizen of the United States, residing at Boston, in the county of Suffolk and Commonwealth 5 of Massachusetts, have invented and produced a new and original Design for a Body for Rotary Trimmer-Cutters, of which the following is a specification.

Figure 1 shows my design looking at it from one end. Fig. 2 shows it in the dotted line x , and Fig. 3 shows the opposite end.

The leading feature of my design consists of a frusto-conical body presenting at its larger base a circular plate or end and at its smaller base an annular or ring-like wall and a central stud within said wall, the inner side of said wall being tapered or flared outwardly from the smaller base toward the inner side of the larger base.

20 The frusto-conical body A of the design pre-

sents at its larger base a circular plate or end a and at its smaller base an annular or ring-like wall a' and a central stud a^2 within said wall, the inner side of the wall being tapered or flared outwardly, as at a^3 , from the smaller 25 base toward the inner side of the larger base.

Having described my invention, what I claim as new, and desire to secure by Letters Patent, is—

The design for a rotary-trimmer-cutter 30 body, substantially as herein shown and described.

In testimony whereof I have signed my name to this specification in the presence of two subscribing witnesses.

EUGENE CHILDS.
